UNITED STATES PATENT OFFICE.

LOUIS E. F. WACHTER, OF NEW YORK, N. Y.

WATCH CRYSTAL AND BEZEL.

1,288,307.

Specification of Letters Patent. Patented Dec. 17, 1918.

Original application filed December 14, 1915, Serial No. 66,676. Divided and this application filed February 16, 1918. Serial No. 217,474.

To all whom it may concern:

Be it known that I, LOUIS E. F. WACHTER, a citizen of the United States, and a resident of New York city, county and State of New

5 York, have invented certain new and useful Improvements in Watch Crystals and Bezels, of which the following is a specification, reference being had to the drawings herein referred to which are made a part 10 hereof and which is a division of my application for Letters Patent originally filed December 14, 1915, Serial No. 66,676.

This invention relates to watches, and particularly to the crystal or transparent face 15 covering and associated parts such as the bezel. Among the particular objects is the production of a crystal and means of support therefor, which will be secure and which will accommodate variations in size 20 of the crystal due to temperature changes or shrinking or distortion, which may occur in crystals made of celluloid or like material.

In the accompanying drawings Figure 1 25 illustrates a diagonal cross-section through a crystal and its supporting bezel. Fig. 2 shows a similar cross-section with an alternate manner of insertion of the crystal.

The crystal A is surrounded by a bezel F, having an overlapping inwardly projecting 30 annular portion f, while the snap shoulder f' on the inside serves for engagement with the edge of the crystal A. A small annular groove a in the outer face of the crystal, is so formed that the edge of the bezel projection f will engage it so that the overlapping portion of the bezel lying annularly around the edge of the crystal A will have a broad 35 engagement with the surface of the crystal, and as may be desired the spring of the material of the bezel may be made such as to accommodate any slight irregularities in 40 size. In any case the construction affords

a joint between the bezel and the outer crystal surface, which will prevent the ingress of water or moisture between the crystal 45 and bezel.

The crystal may be snapped into the bezel from the inside, and the bezel is then secured to the watch case center in any usual manner; and when desired the annular bezel portion 50 f may be so arranged and proportioned as to insert the crystal from the outside and the annular portion f then rolled down into the crystal as shown as illustrated in Fig. 2.

It will be seen that the edge of the crystal 55 is held on the inside and outside between the two portions of the bezel f and f', and in the form shown the outer flange of the bezel is longer than the inner flange and presses into the crystal above the edge. 60

It will be understood that my invention may be modified in forms from what I have herein specifically shown and described, and that the crystal may be made of various 65 materials and dimensions, without departing from the spirit of my invention, but what I claim and desire to secure by Letters Patent is:

In a watch, a crystal, a circular groove on 70 the face of said crystal, a bezel, an overlapping portion of said bezel adapted to cover the peripheral border of the crystal and engage the circular groove, an annular groove in said bezel to receive the peripheral edge of said crystal, and a radially inward 75 flange extending from the bezel on the inner side of said groove forming a support for the crystal.

Signed at New York, this 14th day of February, 1918.

LOUIS E. F. WACHTER.
